DESIGN.

W. S. GRAFTON.

CENTER PIECE FOR METALLIC CEILINGS.

No. 23,081.

Patented Feb. 20, 1894.

UNITED STATES PATENT OFFICE.

WILLIAM S. GRAFTON, OF WHEELING, WEST VIRGINIA, ASSIGNOR TO THE
WHEELING CORRUGATING COMPANY, OF SAME PLACE.

DESIGN FOR A CENTER-PIECE FOR METALLIC CEILINGS.

SPECIFICATION forming part of Design No. 23,081, dated February 20, 1894.

Application filed January 24, 1894. Serial No. 497,937. Term of patent 7 years.

To all whom it may concern:

Be it known that I, WILLIAM S. GRAFTON, a citizen of the United States, residing at Wheeling, in the county of Ohio and State of West Virginia, have invented and produced a new and original Design for Center-Pieces for Metallic Ceilings, of which the following is a specification, reference being had to the accompanying drawing, forming part hereof, which shows a center-piece for metallic ceilings designed according to my invention.

My design consists of a center piece for metallic ceilings ornamented as follows:

The plate A has on each of its edges a rib or projection a, in which are arranged at equal distances apart concaved projections a'. In the center of the plate there is a circular, convex projection B, and around this projection is a circular series of concaved circular projections C, on each side of which there is a circular rib D. Within the circular rib on the inner side of the circular projections C, and radiating from the central projection B, is a series of ribs forming heart-shaped figures E, and also a series of ribs forming leaf-shaped figures F. The projection B, and the inner ends of the figures E and F are arranged somewhat above the plane of the circular ribs D. From the outer circular rib D, projects a series of ribs which are so arranged as to form

leaf-shaped figures G. Each leaf-shaped figure contains a rib g, from which radiate other ribs g', and represent the veins of the leaves. The inner ends of the leaves, or the stems, are connected together and form a continuous rib 35 around the outer circle D. This continuous rib is arranged on a portion of the plate raised above the plane of the ribs D, and the plate is inclined or slopes from this portion toward the outer edge on each side. Interspersed in 40 the leaf-shaped figures at equal distances apart, are circular figures H, having radial depressions h, and forming representations of daisies.

The essential feature of my design is the 45 center piece for metallic ceilings herein shown and described, in which a central figure formed of leaf-shaped and heart-shaped ribs are surrounded by a series of circular projections which are in turn surrounded by a series of 50 ribs forming leaf-shaped projections.

I claim--

The design for a center piece for metallic ceilings herein shown and described.

In testimony whereof I have hereunto sub- 55 scribed my name.

WILLIAM S. GRAFTON.
